UNITED STATES PATENT OFFICE.

JULIUS MILLER AND DAVID MACOWSKY, OF SAN FRANCISCO, CALIFORNIA.

DESIGN FOR A DRESS.

Application filed November 29, 1920. Serial No. 427,251. Term of patent 3½ years.

To all whom it may concern:

Be it known that we, JULIUS MILLER and DAVID MACOWSKY, citizens of the United States, residing at the city and county of San Francisco, and State of California, have invented a new, original, and ornamental Design for Dress, of which the following is a specification, reference being had to the accompanying drawings, forming part thereof.

Fig. 1 is a view in front elevation of a dress embodying our new design.

Fig. 2 is a view in rear elevation of a dress embodying our new design.

We claim the ornamental design for a dress as shown.

JULIUS MILLER.
DAVID MACOWSKY.
